(57) **CLAIM**

The ornamental design for a cosmetics bottle, as shown and described.

DESCRIPTION

FIG. 1 is a top perspective view of a first embodiment of a cosmetics bottle according to our new and ornamental design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and

FIG. 7 is a bottom plan view thereof.

FIG. 8 is a top perspective view of a second embodiment of a cosmetics bottle according to our new and ornamental design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The dash-dot broken lines represent the boundaries of the claimed design and form no part of the claim. The evenly dashed broken lines outside the boundary lines represent portions of the cosmetics bottle that form no part of the claimed design.

1 Claim, 12 Drawing Sheets
